(57) **CLAIM**

The ornamental design for a microphone stand, as shown and described.

DESCRIPTION

FIG. 1 is a perspective view of a microphone stand showing my new design;

FIG. 2 is a front view thereof;

FIG. 3 is a rear view thereof;

FIG. 4 is a left-side view thereof;

FIG. 5 is a right-side view thereof;

FIG. 6 is a plan view thereof;

FIG. 7 is a bottom plan view thereof; and,

FIG. 8 is a perspective view thereof.

The microphones are shown for illustrative purposes only and form no part of the claimed design.
